UNITED STATES PATENT OFFICE

166,145

CRADLE FOR WINE BOTTLES

Earl F. Cook, Marblehead, Mass.

Application April 1, 1950, Serial No. 8,924

Term of patent 14 years

(Cl. D58—26)

To all whom it may concern:

Be it known that I, Earl F. Cook, a citizen of the United States, residing at Marblehead, in the county of Essex and State of Massachusetts, have invented a new, original, and ornamental Design for a Cradle for Wine Bottles, of which the following is a specification, reference being had to the accompanying drawing, forming part thereof.

Fig. 1 is a perspective view of a cradle for wine bottles, showing my new design;

Fig. 2 is a front view;

Fig. 3 is a rear view;

Fig. 4 is a side view; and

Fig. 5 is a top plan view.

I claim:

The ornamental design for a cradle for wine bottles, as shown.

EARL F. COOK.
